US0D1103706S

(12) **United States Design Patent** (10) **Patent No.:** **US D1,103,706 S**
(45) **Date of Patent:** **** Dec. 2, 2025**

(54) **SERVING PLATE**

- (71) Applicant: **Bethrick, Inc.**, Elroy, WI (US)
(72) Inventor: **Richard A. Kellow, Jr.**, Elroy, WI (US)
(73) Assignee: **Bethrick, Inc.**, Elroy, WI (US)
(**) Term: **15 Years**
(21) Appl. No.: **29/877,779**
(22) Filed: **Jun. 12, 2023**

Related U.S. Application Data

- (60) Continuation of application No. 29/843,268, filed on Jun. 20, 2022, which is a division of application No. 29/800,100, filed on Jul. 19, 2021, now Pat. No. Des. 955,176, which is a continuation of application No. (Continued)

(57) **CLAIM**

The ornamental design for a serving plate as shown and described.

DESCRIPTION

FIG. 1 is a top perspective view of the claimed design according to a first embodiment;

FIG. 2 is a second top perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a cross section view of the claimed design as shown in FIG. 3;

FIG. 10 is a top perspective view of the claimed design according to a second embodiment;

FIG. 11 is a second top perspective view thereof;

FIG. 12 is a top plan view thereof;

FIG. 13 is a bottom plan view thereof;

FIG. 14 is a front elevation view thereof;

FIG. 15 is a rear elevation view thereof;

FIG. 16 is a right side elevation view thereof;

FIG. 17 is a left side elevation view thereof; and,

FIG. 18 is a cross section view of the claimed design as shown in FIG. 12.

The ornamental design which is claimed is shown in solid lines in the Figures. Broken lines of equal length dashes are for illustrative purposes and form no part of the claimed design. Broken lines of unequal length dashes (i.e., dash-dot) define bounds of the claimed design.
